UNITED STATES PATENT OFFICE.

CHARLES L. MARTI, OF WEST ORANGE, NEW JERSEY.

DESIGN FOR PANEL FOR RADIO RECEIVING SETS.

Application filed June 25, 1928. Serial No. 27,263. Term of patent 3½ years.

To all whom it may concern:

Be it known that I, CHARLES L. MARTI, a citizen of the United States, residing at West Orange, in the county of Essex and State of New Jersey, have invented a new, original, and ornamental Design for Panels for Radio Receiving Sets, of which the following is a specification, reference being had to the ac-

companying drawing, forming part thereof. The drawing illustrates the design of panel or escutcheon plate in front elevation.

I claim:

The ornamental design for panel for radio receiving sets as shown.

CHARLES L. MARTI.
